CLAIM

The ornamental design for a building façade extrusion-intermediate as shown and described.

DESCRIPTION

FIG. 1 is a front perspective view of the building façade extrusion-intermediate of the instant invention;

FIG. 2 is a top view thereof;

FIG. 3 is a bottom view thereof forming a mirror image of the top view;

FIG. 4 is a left side view thereof;

FIG. 5 is a right side view thereof;

FIG. 6 is a front view thereof; and,

FIG. 7 is a back view thereof.

The drawings contain symbolic break lines in FIGS. 1 and 4-7. The portions of the article between the break lines forms no part of the claimed design.

1 Claim, 6 Drawing Sheets
